(57) **CLAIM**

The ornamental design for a CONTROL ACCESSORY as shown and described.

DESCRIPTION

FIG. 1 is a top isometric view of a first embodiment of a CONTROL ACCESSORY;

FIG. 2 is a bottom isometric view of the CONTROL ACCESSORY shown in FIG. 1;

FIG. 3 is a front view of the CONTROL ACCESSORY shown in FIG. 1, the rear view is identical;

FIG. 4 is a right side view of the CONTROL ACCESSORY shown in FIG. 1, the left side view is identical;

FIG. 5 is a top view of the CONTROL ACCESSORY shown in FIG. 1;

FIG. 6 is a bottom view of the CONTROL ACCESSORY shown in FIG. 1;

FIG. 7 is a top isometric view of a second embodiment of a CONTROL ACCESSORY;

FIG. 8 is a bottom isometric view of the CONTROL ACCESSORY shown in FIG. 7;

FIG. 9 is a front view of the CONTROL ACCESSORY shown in FIG. 7, the rear view is identical;

FIG. 10 is a right side view of the CONTROL ACCESSORY shown in FIG. 7, the left side view is identical;

FIG. 11 is a top view of the CONTROL ACCESSORY shown in FIG. 7; and

FIG. 12 is a bottom view of the CONTROL ACCESSORY shown in FIG. 7.

The broken lines represent portions of the CONTROL ACCESSORY that form no part of the claimed design.

1 Claim, 12 Drawing Sheets
